UNITED STATES PATENT OFFICE.

PARVIN WRIGHT, OF LOS ANGELES, CALIFORNIA.

ELEVATOR.

987,663.

Specification of Letters Patent. Patented Mar. 21, 1911.

Application filed August 25, 1904. Serial No. 222,088.

To all whom it may concern:

Be it known that I, PARVIN WRIGHT, a citizen of the United States of America, residing at Los Angeles, in the county of Los Angeles, State of California, have invented certain Improvements in Elevators, of which the following is a specification.

This invention relates to elevators, and more particularly to passenger elevators, and the general object of the invention is to provide an elevator possessing all the advantages of a hydraulic elevator, but operated indirectly by an electric motor.

A further object of the invention is to provide a constant liquid pressure substantially equal to the weight of the hydraulic piston and car and car lifting mechanism, liquid under such pressure being delivered to a centrifugal pump and by such pump increased sufficiently to operate the car.

A further object is to reduce both the cost of manufacture and the operating expense of such an elevator.

A further object of the invention is to provide a hydraulically operated elevator in which is utilized a pressure tank, in which is maintained a constant pressure, and in connection therewith a suitable pump, such for instance as a centrifugal pump, driven by a suitable motor, for increasing the pressure from such pressure tank to the lifting piston when it is desired to raise the car, and utilizing the pressure of the tank to counterbalance the car or cage.

A further object of the invention is to so connect such pumping means with such hydraulic operating means that said pump may be driven in one direction regardless of the direction of the elevator lift or cage.

Other and further objects and ends in view will hereinafter appear from the detail description of construction and operation.

The invention consists further in various constructions and combinations of parts, all as hereinafter described and particularly set forth in the claims, and will be more readily understood by reference to the accompanying drawings forming a part of this specification, and in which,

Figure 1 is a longitudinal elevation, partly in section, of an elevator embodying my invention. Fig. 2 is an elevation of the main valve, showing the pilot valve in normal position with its casing removed. Fig.

3 is a longitudinal sectional view of the main or commutative valve on the line X³—X³ of Fig. 8, showing the pistons in normal positions, the pilot valve having been turned and the pressure being about to enter the 60 pilot cylinder, to start the elevator up. Fig. 4 is a similar view showing the positions the pistons occupy when the elevator cage is being raised. Fig. 5 shows the rocking arm and pilot valve in the positions 65 which they assume when the pistons of the main valve are in the positions of Fig. 3, the pilot valve being shown in dotted lines and the lower electrical contact is shown in this figure as having been made to start the 70 pump. Fig. 6 shows the rocking arm and pilot valve in the positions which they assume when the pistons of the main valve occupy the positions shown in Fig. 4, the pilot valve being shown in dotted lines and 75 the lower electrical contact having been released from the position of Fig. 5, and the upper contact having been automatically substituted. Fig. 7 is an enlarged sectional view of the pilot valve. Fig. 8 is a plan 80 view of the apparatus on the line X⁸—X⁸ of Fig. 1. Fig. 9 is a sectional view of the throttle valve. Fig. 10 is a longitudinal elevation similar to Fig. 2, showing the check valve and pump. Fig. 11 is a transverse 85 sectional view of the main valve taken on the line X¹¹—X¹¹ of Fig. 2, looking toward the pressure tank or retort, the electrical devices being removed for clearness. Fig. 12 is a sectional plan view of the main valve on 90 the line X¹²—X¹² of Fig. 3, the electrical devices being removed. Fig. 13 is a vertical elevation of the lifting cylinder, in midway position, showing the levers for controlling the throttle valve. 95

As shown in the drawings, 2 represents the main valve cylinder or casing, which may be of any suitable or preferred shape or construction. This cylinder has its interior separated into two chambers, 3, 3', connected together by the cylinders 4, 4, spaced apart by the central partition 5.

6, 6' represent piston rods carrying valves, 7, 7', and having heads, 8, 8', which extend into the piston chambers 9, 9', preferably 100 below the casing or cylinder 2, and either formed separate therefrom or integral therewith, as preferred. The casing 2 is provided on opposite sides with ports 10, 11, and 12, 13, the ports 11, 13 being preferably 110

opposite one another and communicating with the chambers of the piston valve cylinders 4, through series of peripheral inlets, as shown. The port 11 is provided with a small port 14, outside the peripheral inlets of the cylinder 4. This port 14 is connected with a pipe 15 leading to the port 16 of the pilot valve. The port 17 is connected by a pipe 18 with the port 19 of the pilot valve. The ports 20, 20' of the pilot valve are connected respectively by pipes 21, 21' with ports 22, 22' opening into the piston chambers 9', 9.

The pilot valve 23 comprises a segmental plate having a recess in its under face, and the plate is mounted on a shaft 24 which extends through the central partition 5 and is provided on its opposite end with an arm 25. A pilot valve chamber 26 is formed by a recess in the casting of the main valve cylinder, this recess being closed by a plate 27, suitably held in place and suitably packed.

28 represents a rocking arm, and through this rocking arm, about the center thereof, passes a pin 29, on which is fixed an arm 30. This arm 30 is mounted on a bolt or shaft 31 extending through the central partition 5, at a point above the shaft 24. The upper end of the rocking arm 28 is provided with an interior rack 32 adapted to mesh with a pinion 33, carried on a shaft 34 extending through the chamber 3 of the main valve casing. This shaft 34 is suitably packed and within the chamber 3 is provided with a pinion 35 adapted to mesh with racks 36, 36' extending upward from the piston valves 7, 7' respectively.

The recess or channel in the inner face of the plate or pilot valve 23 is long enough to cover or communicate with the openings 19, 20 and 20' when the plate is standing in its normal position as shown in Figs. 2 and 6, but when the plate is shifted to one side or the other the recess will only cover the port or opening 19 and one of the others, as 20', as shown in Fig. 5. When standing in its normal position the pressure of the water from the port 16 is shut off from and can not communicate with either of the ports or openings 20 and 20' and the pressure from the other three ports, 19, 20 and 20' is equalized and the valve mechanism remains stationary. As soon, however, as the plate or pilot valve is shifted so as to uncover one or the other of the ports 20 or 20' and place it in communication with the port 16 the excessive pressure from that port caused by the action of the pump which has been started simultaneously with the shifting of the pilot valve, will pass down through the respective pipe to the lower end of the piston chamber and thereby actuate the valve mechanism so as to cause the water to pass through the commutative valve to or from

the elevating mechanism as it is desired to move the cage upward or downward.

The port 12 is connected by a suitable pipe with the pressure tank 37 and in the pipe is preferably interposed a valve 38. 70 The port 10 is connected with the piston chamber of the hydraulic lifting mechanism by a pipe 39, and interposed in this connecting pipe is a throttle valve 40, which is controlled and operated as will be herein-after described. The port 13 is connected with a pipe 41 which leads to the centrifugal pump, indicated by A, while the port 11 is connected with a pipe 42 leading from the centrifugal pump A.

43 represents the casing of the lifting piston and 44 the piston. On top of the casing 43 is suitably mounted a guide frame 45, and the piston 44 carries at its top a spider 46, in which is mounted a suitable shaft upon which the pulleys 47, 47' are loosely mounted. In the frame 48, supporting the cylinder or casing 43, and below such cylinder or casing, pulleys 49, 49' are loosely mounted in a suitable shaft. 80

B represents a lift or car, which may be of the ordinary or any preferred construction, and may run in the ordinary or any preferred guides. This car is connected by a cable 50, which extends over suitable pulleys 51, 52, suitably arranged at the top of the elevator shaft and in suitable relation to the position of the lifting piston 44. From the pulley 52 the cable 50 extends down about the pulley or sheave 49', thence up the opposite side of the cylinder 43 and over the pulley or sheave 47', thence down and about the pulley 49, thence up and over the pulley 47, and thence to anchorage, as for instance, at 53 in the frame 48. 90

The valve 40 is mounted on a shaft 54 which is provided, outside the valve casing, with an arm or lever 55 that normally stands longitudinally of or parallel with the pipe 39. A rod 57 is pivotally connected with one end of the lever and extends up alongside of the cylinder 43 and the frame 45. Two arms 58 and 58' are mounted on one side of the frame with one end of each pivotally connected with the rod 57 and the other end located in the path of a wheel 59 and adapted to be actuated thereby and thus automatically close the valve through the rod 57 and lever 55 when the spider or bracket 46 reaches the limit of its movement in either direction. The roller or wheel 59 is preferably secured to the spider by means of a stub axle 60 and each arm is provided with a finger 58a which projects therefrom at right angles to the base line of the arm and is so located that when the wheel 59 engages with either arm and moves it to its limit the finger will be drawn into the path of the wheel after the wheel has so engaged, and when the wheel starts on 100

its return movement it will engage with said finger and thereby rock the arms back into their normal position and thus open the valve 40. A weight 56 is preferably adjustably secured to the lever 55 to counterbalance any excessive weight or undue friction that might occur, thus permitting the lever 55 to stand in any position to which it may be moved.

10 In the pressure tank or reservoir 37, I provide a float 62, suitably located so that the air above said float forms an air cushion adapted to hold the float against the liquid. This float serves to prevent the pulsation or 15 bubbling of the liquid in the pressure tank. The floating partition 62 also serves to reduce the absorption of air in the body of water in the tank. It will be understood that as the water is forced into the tank it 20 compresses the air in the upper portion of the tank and this tends to increase the amount of air taken up by the water. The effect of this is to continually drain the tank of air as the water charged with air passes 25 to other parts of the system and the provision of the floating partition reduces this loss of air to a minimum. An operating arm 63 has one end connected with the rocking arm 28 and its other end connected with the 30 usual elevator controlling device, as shown best in Fig. 1.

The pump A is operated by an electric motor C, connected by suitable circuits with a rheostat D. This rheostat may be of the 35 particular construction and arrangement shown in the drawings, or of any ordinary or preferred form or construction. The rocking arm 28 is adapted to complete the circuits through the rheostat to the electric 40 motor. 64 represents a circuit breaker, which may be of the ordinary or any preferred construction or arrangement. As shown, it consists of a pivoted arm, carrying at one end a contact plate, and at the other end a roller 45 adapted to contact with a shoulder or projection 65 on the upper end of the rocking arm 28. The contact plate 64 is adapted to complete the electric circuit through the contacts 66. A similar circuit breaker 67 is arranged at the lower end of the rocking arm 50 28 and is likewise operated by the movement of the rocking arm and adapted to complete the circuit, when the rocking arm is in the position of Fig. 5. It will be noted, as 55 shown in Fig. 1, that when the rocking arm is in a vertical position and the piston 44 is stationary, both the circuit breakers 64 and 67 are held out of contact with the contacts and the circuit is broken and the electric 60 motor at rest.

The operation is as follows: Assume the valve 38 to have been opened. The elevator operator throws his lever and pulls forward the rod 63 thereby pulling forward the lower 65 end of the operating arm 28. This motion

of the arm 28 throws the valve 23 into the position of Fig. 5, throwing the ports 16 and 20 into communication with one another and the ports 20' and 19 into communication under the valve 23. This reciprocation of the 70 arm 28, as shown in Fig. 5, also releases the circuit breaker 67, so that the electrical circuit is completed through the same and the electric motor put in operation, thereby starting the pump. Liquid is then forced 75 through the port 14, pipe 15, port 16, port 20, down the pipe 21, into the piston chamber 9' and against the piston 8', forcing the same upward, thereby throwing up the valve 7', and through the rack bar 36' motion is 80 imparted to the pinion 35, and the rack bar 36 is moved down, carrying downward the valve 7 and piston 8. The liquid forced out from the chamber 9 passes out through the port 22', pipe 21', through ports 20' and 19, 85 under the valve 23 and thence through pipe 18 and port 17 into the pipe leading to the suction pipe of the pump. This operation of the pinion 35 causes the shaft 34 to be rotated, and as the pinion 33 is fixed on this 90 same shaft, the pinion 33 is correspondingly rotated, and the operating arm 28 thrown to the position of Fig. 6. As the arm 63 is held stationary, this movement of the upper end of the arm 28, through the pinion 33 95 and rack 32, causes the lower end of the arm 28 to be thrown back to its initial position (that is, causes the lower end of the arm 28 to occupy the same position that it occupied when at rest) and causes the arm 100 25 to be thrown to a vertical position, thereby automatically operating the valve 23 to move the same from the position of Fig. 5 to its normal position, so that the ports 19, 20 and 20' are in communication. This automatic throwing of the arm 28 from the position of Fig. 5 to the position of Fig. 6 causes the projection or lug 65 to be withdrawn from the circuit breaker 64, allowing the electric circuit to be completed thereby, 105 110 and the reciprocation of the lower end of the arm 28 back to its normal position brings the lower end of the arm again in contact with the roller of the circuit breaker 67, breaking the circuit, which had been completed thereby. It is obvious that if the arm 63 had been thrown in the opposite direction, the lower end of the rocking arm 28 would have been thrown to the left instead of pulled to the right, and, consequently, the 115 120 valve 23 would have been operated to throw the ports 16 and 20' into communication; this would have caused the forcing up of the piston 8 and valve 7.

When the piston valves 7, 7' are in the 125 positions of Fig. 4, liquid from the tank 37 flows into the pump through the duct 13. The pipe 41 represents the suction pipe of the pump and the pump is aided in producing the requisite hydraulic pressure to raise 130

the piston 44, by the pressure of the liquid in the pressure tank 37. From the pump the liquid is forced through the pipe 42, duct 11 into the chamber 3 and out the port 10 and thence through the pipe 39, valve 40 to the piston cylinder 43. When the elevator cage or lift is lowered the pump is operated in the same direction, but the flow of liquid is reversed by the reversal of the main valve 10 and the flow of liquid from the piston cylinder 43 is through the pipe 39, port 10 into the chamber 3 of the main valve. In this descending operation, the piston valve 7 will be in its raised position and piston valve 15 7' in its lowered position. This permits the liquid entering the chamber 3 to pass out the port 13 to the pump and the liquid from the pump is forced through port 11, chamber 3' and port 12 into the pressure tank 20 37, against the pressure in the pressure tank. By constructing and operating an elevator in this manner the pressure upon the liquid in the tank 37 is utilized to counterbalance the weight of the car and thus the necessity 25 of using other counterbalancing means is avoided.

68 represents a check valve which, as shown, is located in the suction pipe of the centrifugal pump. This check valve prevents any back pressure from the pump. It is thus seen that with my elevator the pump operates in the same direction whether the cage is going up or down and that the reversal of the flow of liquid from the pressure 30 tank to the elevator cylinder and vice versa is effectuated by means independent of the operation of the pump. In the appended claims I refer to this means as a commutative valve and include in that term any valve means where- 35 40 by the flow of liquid is reversed between the tank and cylinder irrespective of the operation of the pumping means. The float 62 divides the tank 37 into two compartments, the cubic area of these compartments or 45 chambers varying as the float slides up or down. In the upper compartment I supply compressed air and the float 62 prevents the absorption of this air by the liquid.

I prefer to employ a centrifugal pump for 50 the reason that with such a pump when the exhaust is brought to a stand-still, the centrifugal pump may exhaust its impetus and it is not necessary to provide any brake means for instantly stopping the pump, and 55 the pump therefore is not required to stop the circulation of the liquid, nor is the impact of stopping in any manner carried by the pump in my apparatus.

60 The pressure in the tank 37 is preferably maintained at about 100 lbs. and increased when passing through the pump A to 175 lbs. It is thus seen that the pump A is required only to exercise sufficient energy to 65 raise the liquid from 100 to 175 lbs. pressure, this saving materially the energy re-

quired to operate the pump and car. In descending the weight of the lifting mechanism and car deliver the liquid through the pump to the pressure tank at substantially 100 lbs. pressure requiring the exercise of 70 substantially no energy by the pump in the descending operation. A very decided advantage is thus gained by the use of a centrifugal pump and the pump is not required to stop the circulation of liquid which 75 is accomplished by closing the commutative valve.

Having thus described my invention, I claim as new and desire to secure by Letters Patent:

1. In an elevator, an elevator cylinder, a pressure tank, a conduit therebetween provided with a commutative valve, a closed fluid circuit connected with said valve, a centrifugal pump in said circuit, an electric 80 85 motor for operating the pump, and means connected with said valve for controlling the motor at the time of the operation of the valve.

2. In an elevator, an elevator cylinder, a pressure tank connected therewith, a commutative valve in said connection, a one way pump connected with said valve, a motor for operating the same, a lever provided with means for automatically controlling 90 95 the motor at the time of the operation of the valve, means operatively connected with said lever for controlling the commutative valve, and means for initially and finally operating the lever, said last mentioned means being adapted to be actuated by the operator.

3. In an elevator, an elevator cylinder, a pressure tank connected therewith, a commutative valve in said connection, a one way pump connected with said valve, a motor for operating the same, a lever connected with the valve and provided with a plurality of fulcra, means operatively connected with the lever and fulcra for automatically controlling the valve and means for controlling 100 105 the motor by the lever when the lever is moved.

4. In an elevator, an elevator cylinder, a pressure tank connected therewith, a commutative valve in said connection, a pilot 115 valve for the same, a one way pump connected with the commutative valve, a motor for actuating the pump, a lever connected with said valves and adapted to be actuated by the commutative valve to automatically close the pilot valve and to control the motor, and shifting mechanism connected with the lever and adapted to be actuated by the operator.

5. In an elevator, an elevator cylinder, a pressure tank connected therewith, a commutative valve in said connection, a pilot valve for the same, a one way pump connected with the commutative valve, a motor for actuating the pump, a lever con- 120 125 130

nected with said valves and adapted to be actuated by the commutative valve to automatically close the pilot valve and to control the motor, said lever being provided 5 with two fulcra, and shifting mechanism connected with the lever at one of its fulcra.

6. In an elevator, an elevator cylinder, a pressure tank connected therewith, a commutative valve in said connection, a pilot 10 valve for the same, a one way pump connected with the commutative valve, a motor for the pump, means for manually actuating the pilot valve to open the same and to start the motor, and means for automatically 15 closing the pilot valve and leaving the commutative valve open without stopping the motor.

7. In an elevator, an elevator cylinder, a pressure tank connected therewith, a commutative valve in said connection, a pilot 20 valve for the same, a one way pump connected with the commutative valve, an electric motor for the pump having two switches in its circuit, a lever connected with said 25 valves and adapted to control said switches so as to open both of them or to close either of them when the other one is open, and means for manually actuating said lever.

8. In an elevator, an elevator cylinder, a pressure tank connected therewith, a commutative valve in said connection, a motor 30 for the commutative valve, a four ported valve chamber for the valve for the motor, a one-way pump connected with the commutative valve and with two of the ports of 35 said chamber, a recessed valve in said chamber adapted to open communication between three of said ports, or only two of them, a motor for the pump, controlling means for 40 moving said recessed valve for opening communication between two of said ports and to start the motor and to open communication between three of them when the motor is either running or standing still, and means 45 for manually actuating said controlling means by the operator.

9. In an elevator, an elevator cylinder, a pressure tank connected therewith, a commutative valve in said connection provided 50 with two piston valves, each of said piston valves being provided with a rack, a shaft and two pinions adapted to be actuated by 55 said racks, a lever provided with a rack at one end adapted to be actuated by one of said pinions, a pilot valve connected with said lever and adapted to control the movements of said piston valves, a one way pump connected with the commutative valve, a motor for the pump adapted to be controlled 60 by said lever, and means for manually actuating said lever by the operator.

10. In an elevator, an elevator cylinder, a pressure tank connected therewith, a commutative valve in said connection comprising 65 a double chambered casing having two

elongated chambers at one end and two centrally perforated ducts at the middle for connecting the chambers in the casing, a piston valve in each duct having a piston at one end in one of said elongated chambers 70 and a rack at the other, a shaft and two pinions, one of the pinions being in engagement with said racks, a lever having a rack at one end in engagement with the other pinion, a one way pump connected with the 75 commutative valve casing, a pilot valve communicating with the pump and with the elongated chambers, means for connecting the pilot valve with the lever so that when the lever is manually operated the piston 80 valves will be automatically actuated to direct the passage of the liquid through said commutative valve, a motor for the pump adapted to be controlled by said lever, and means connected with the lever for actuating 85 the same by the operator.

11. A reversing valve for elevators comprising two chambers having independent ducts and common ducts, piston cylinders into which said common ducts communicate, 90 piston valves in said cylinders, said piston valves having operating pistons and provided with racks, piston chambers wherein said pistons operate, a pilot valve operatively connected with said piston chambers, 95 a shaft for the pilot valve, a rocker arm provided with a rack, a connection between said arm and shaft, a shaft, and pinions on said shaft meshing with said racks.

12. In an elevator, an elevator cylinder, a pressure tank connected therewith, a commutative valve in said connection, means for actuating the same, a pump connected with 100 said valve, a four ported valve chamber, two of said ports communicating with the 105 actuating means for the commutative valve and the other two communicating with the pump, a recessed pilot valve adapted to place the pump ports in communication with either of the other ports and to place the 110 port that communicates with the suction of the pump in communication with both of the ports to the commutative valve at the same time, a motor for the pump, and means for controlling the motor when the valves 115 are actuated.

13. In an elevator, an elevator cylinder, a pressure tank connected therewith, a commutative valve in said connection, means for actuating the same a centrifugal pump 120 connected with said valve, a four ported valve chamber, two of said ports being connected with the actuating means for the commutative valve, and the other two communicating with the pump, a segmental plate 125 rotatably mounted in said chamber and provided with a recess in its under face adapted to establish communication between the port to the suction of the pump and both of the ports to the commutative valve simultane- 130

ously or to either one of them only, a motor for the pump, and means for actuating said plate and controlling the motor.

14. In an elevator, an elevator cylinder, a pressure tank connected therewith, a commutative valve in said connection, a centrifugal pump connected with said valve, controlling means, a motor for said valve adapted to take fluid from the discharge 10 side of the pump to actuate said valve and simultaneously therewith to discharge fluid from the valve controlling mechanism into the suction of the pump, a motor for the pump, and means for controlling the pump 15 when said valve actuating mechanism is operated.

15. An elevator comprising a pressure tank, a lifting cylinder, a commutative valve and pumping means, said lifting cylinder 20 being connected with said pressure tank through said pumping means and valve, mechanism to actuate the valve to reverse the direction of flow of liquid through said commutative valve, an electric motor 25 operatively connected with said pumping means, circuits for said motor, and circuit making and breaking means carried by said valve mechanism and operated thereby to make and break the circuits of said motor.

16. An elevator comprising a pressure tank, a lifting cylinder and piston, a commutative valve and pumping means, said valve and pumping means being constructed and arranged to permit the pumping means to be operated in the same direction regardless of the direction of movement of the piston, and means by which the discharge from the pump may be utilized to operate the valve. 30 35

17. A reversing valve for elevators comprising two chambers having independent ducts and common ducts, cylinders into which said common ducts communicate, piston valves in said cylinders, provided with operating pistons, piston-chambers 40 45 wherein said pistons operate, a pilot valve operatively connected with said piston-chambers, a shaft carrying a pinion and operatively connected with said piston valves, and a reciprocating rack meshing with said pinion and actuating said pilot valve. 50

In testimony whereof, I have hereunto set my hand at Los Angeles California this 20th day of August 1904.

PARVIN WRIGHT.

In presence of—
FREDERICK O. LYON,
JULIA TOWNSEND.
